Inventor:

John Stanley Hazell,
By his Att'y, F. H. Richards

UNITED STATES PATENT OFFICE.

JOHN STANLEY HAZELL, OF LONDON, ENGLAND, ASSIGNOR TO UNCHOKEABLE PUMP, LIMITED, OF LONDON, ENGLAND.

IMPELLER FOR CENTRIFUGAL PUMPS.

Application filed November 3, 1922. Serial No. 598,921.

To all whom it may concern:

Be it known that I, JOHN STANLEY HAZELL, a subject of the King of Great Britain, residing in London, England, have invented certain new and useful Improvements in Impellers for Centrifugal Pumps, of which the following is a specification.

This invention relates to impellers for centrifugal pumps and refers to balanced impellers having a single port or passage for the liquid.

With impellers of the type referred to it is sometimes found advisable, in order to secure the most efficient results per horse power of the engine driving the pump, that the diameter of the impeller be reduced.

In practice, with pumps of this type as at present constructed, no provision is made whereby this may be readily effected without destroying the balance of the impeller.

In practice hitherto in order to meet this difficulty it has been usual to provide patterns of different diameter from which castings may be obtained of impellers of the desired diameter.

Such a course as that just referred to is obviously impractical from a commercial point of view as it necessitates the making of a comparatively large number of patterns differing, in some instances, only very slightly in diameter.

The present invention has for its object certain improvements in impellers of the single ported balanced type whereby not only may the diameter of the impeller be readily reduced to the desired extent but this may be effected without interfering with the balance of the impeller.

In order that the invention may be the better understood drawings are appended in which:—

Fig. 1 is a side view of an impeller embodying the present invention,

Fig. 2 is a section on line A A Fig. 1.

Referring to the accompanying drawings *a* indicates the impeller, *b* the single port or passage therein for the liquid and *a'* the balancing chamber.

The chamber *a'* is shown closed but if desired the cover *e* may be omitted and the chamber or cavity left open.

Provision may be made for introducing liquid into the closed chamber, for example a plugged aperture such as indicated in dot-

ted lines at *f* may be provided for this purpose.

Surrounding the impeller upon one or both sides thereof and disposed upon the outer edges of the side members of the impeller is a thickened portion *c*.

d indicates smaller blades or vanes which in addition to imparting an additional impulse to the liquid in the pump casing also tends to balance the heavy metal surrounding the mouth of the port.

In order to vary the diameter of the impeller to meet varying conditions of service it is only necessary to remove the metal from the circumference, by turning in a lathe for example.

In the turning operation metal is also removed from the blades or vanes *d* the amount removed being proportionate to the amount removed from the body of the impeller. By this means the balance is preserved.

By this means a single pattern may serve to produce a large number of impellers and the necessity of providing a number of patterns is avoided, and further any adjustment of the balance which would otherwise be necessary is also avoided.

Claims:

1. A single ported impeller for centrifugal pumps, means for balancing said impeller comprising a plurality of blades upon the sides of the impeller extending to the periphery thereof whereby the diameter of the impeller may be varied without destroying the balance.

2. A single ported impeller for centrifugal pumps, means for balancing said impeller comprising an annular thickened portion upon the periphery of the impeller, a plurality of blades upon the sides of the impeller extending to the periphery whereby the diameter of the impeller may be varied without destroying the balance thereof.

3. A single ported impeller for centrifugal pumps, means for balancing said impeller comprising an annular thickened portion upon the periphery of the impeller, a plurality of blades upon the sides of the impeller extending to the periphery whereby the diameter of the impeller may be varied without destroying the balance thereof, said blades having surfaces designed to impart an additional impulse to the liquid in the pump casing.

4. A single ported impeller for centrifugal pumps, a cavity in said impeller open on one side to permit the entry of the liquid thereto when the impeller is running and thereby assist in the balancing of the impeller, other balancing means comprising a plurality of blades upon the sides of the impeller extending to the periphery thereof whereby the diameter of the impeller may be varied without destroying the balance. 40
5. A single ported impeller for centrifugal pumps, a cavity in said impeller open on one side to permit the entry of the liquid thereto when the impeller is running and thereby assist in the balancing of the impeller, other balancing means comprising an annular thickened portion upon the periphery of the impeller, a plurality of blades upon the sides of the impeller extending to the periphery whereby the diameter of the impeller may be varied without destroying the balance thereof. 45
- 10 6. A single ported impeller for centrifugal pumps, a cavity in said impeller open on one side to permit the entry of the liquid thereto when the impeller is running and thereby assist in the balancing of the impeller, other balancing means comprising a plurality of blades upon the sides of the impeller extending to the periphery whereby the diameter of the impeller may be varied without destroying the balance thereof. 50
- 15 7. A single ported impeller for centrifugal pumps, a cavity in said impeller, a closure for said cavity, means permitting the introduction of liquid to said closed cavity to balance the impeller, other balancing means comprising the introduction of liquid into said closed cavity to balance the impeller, other balancing means comprising an annular thickened portion upon the periphery of the impeller, a plurality of blades upon the sides of the impeller extending to the periphery whereby the diameter of the impeller may be varied without destroying the balance thereof. 55
- 20 8. A single ported impeller for centrifugal pumps, a cavity in said impeller, a closure for said cavity, means permitting the introduction of liquid to said closed cavity to balance the impeller, other balancing means comprising a plurality of blades upon the sides of the impeller extending to the periphery whereby the diameter of the impeller may be varied without destroying the balance thereof. 60
- 25 9. A single ported impeller for centrifugal pumps, a cavity in said impeller, a closure for said cavity, means permitting the introduction of liquid into said closed cavity to balance the impeller, other balancing means comprising a plurality of blades upon the sides of the impeller extending to the periphery whereby the diameter of the impeller may be varied without destroying the balance thereof, said blades having surfaces designed to impart an additional impulse to the liquid in the pump casing. 65
- 30 35 7. A single ported impeller for centrifugal pumps, a cavity in said impeller, a closure for said cavity, means permitting the introduction of liquid into said closed cavity to balance the impeller, other balancing means comprising a plurality of blades upon the sides of the impeller extending to the periphery whereby the diameter of the impeller may be varied without destroying the balance thereof, said blades having surfaces designed to impart an additional impulse to the liquid in the pump casing.
7. A single ported impeller for centrifugal pumps, a cavity in said impeller, a closure for said cavity, means permitting the introduction of liquid into said closed cavity to balance the impeller, other balancing means comprising an annular thickened portion upon the periphery of the impeller, a plurality of blades upon the sides of the impeller extending to the periphery whereby the diameter of the impeller may be varied without destroying the balance thereof, said blades having surfaces designed to impart an additional impulse to the liquid in the pump casing.

In testimony whereof I have hereunto set my hand in the presence of two witnesses.

JOHN STANLEY HAZELL.
